Primary Examiner—Antoine Duval Davis**Attorney, Agent, or Firm**—Davis Chin**[57] CLAIM**

The ornamental design for a mini faulted circuit indicator, as shown and described.

DESCRIPTION

FIG. 1 is a front elevational view of a mini faulted circuit indicator showing my design;

FIG. 2 is a top plan view of the design shown in FIG. 1;

FIG. 3 is a right side elevational view of the design shown in FIG. 1;

FIG. 4 is a bottom view of the design shown in FIG. 1;

FIG. 5 is a back view of the design shown in FIG. 1; and,

FIG. 6 is a perspective view of the design shown in FIG. 1.
